UNITED STATES PATENT OFFICE.

REINHARDT H. BROWN, OF LAPORTE, INDIANA.

CHILD'S COLLAPSIBLE SULKY.

1,222,179.

Specification of Letters Patent.

Patented Apr. 10, 1917.

Application filed January 3, 1916. Serial No. 89,782.

To all whom it may concern:

Be it known that I, REINHARDT H. BROWN, a citizen of the United States, and a resident of Laporte, in the county of Laporte and State of Indiana, have invented certain new and useful Improvements in Children's Collapsible Sulkies, of which the following is a full, clear, and exact specification.

My invention is concerned with children's collapsible sulkies of the type shown in my Patent No. 1,074,349, dated September 30, 1913, but is an improvement on the same in that it employs a folding draft-tongue, which, when it is folded back on the seat, serves to collapse the mechanism positively, except the wheel frames, which are merely unlocked, and fold automatically as soon as the sulky is lifted from the floor for transportation by hand. This enables me to produce a sulky that is collapsed much more easily and with less noise and wear and tear on the parts than has been possible heretofore.

My invention is further concerned with a novel adjustment for the seat back of such vehicles.

My invention is further concerned with certain novel springs for the seat, which support the same yieldingly from the main frame, and yet do not interfere at all with the proper collapsing of the elements.

My invention is further concerned with certain novel combinations of the elements going to make up such a sulky, as will be fully described in the following specification and particularly pointed out in the claims.

To illustrate my invention, I annex here-to four sheets of drawings, in which the same reference characters are used to designate identical parts in all the figures, of which,—

Figure 1 is a side elevation of the sulky erected;

Fig. 2 is a top plan view in section on the line 2—2 of Fig. 1;

Fig. 3 is a front elevation in section on the line 3—3 of Fig. 1;

Fig. 4 is a central longitudinal section on the line 4—4 of Fig. 2;

Fig. 5 is an inverted plan view of the rear portion of the cart;

Fig. 6 is a side elevation, on a larger scale, of the sulky collapsed and standing on the floor;

Fig. 7 is a detail in section on the line 7—7 of Fig. 2;

Fig. 8 is a detail in section on the line 8—8 of Fig. 7;

Fig. 9 is a detail in section on the line 9—9 of Fig. 6;

Fig. 10 (Sheet 1) is a detail in section, on a larger scale, on the line 10—10 of Fig. 3; and

Fig. 11 is a detail in central longitudinal section through the tongue-latching mechanism.

The main frame of the cart is generally rectangular in its outlines, and is made up of the two side bars 12, which are preferably formed of tubing, and which are connected near their rear ends by the cross bars 13, preferably made of a bar of metal bent in a generally U-shape and having the sides 14 thereof riveted to the bars 12 with the ends 15 thereof twisted and curled as shown to form a pair of the four supports upon which the sulky stands when collapsed and in the position shown in Fig. 6. Toward their forward ends the tubes 12 are bent inward, as seen at 16, to produce a narrowed portion, and the forward ends are curved at 17 and have their extreme ends flattened, as seen at 18, and riveted to the cross piece 19, which has the recess 20 therein for the locking mechanism to be subsequently described. The rear ends of the bars 12 are curved downward, as seen at 21, and flattened, and have the small wheels 22 journaled thereon, these wheels serving as a pair of the four supports to hold the sulky in the vertical position shown in Fig. 6, and which wheels are also used in the customary manner in drawing the sulky up and down over curb stones or steps.

The seat 23 preferably consists of a substantially square piece of wood or some other strong, light-weight material of suitable thickness, and which may be cushioned, as shown, as much as may be desired, and the rear edge of this seat 23 is suitably secured to the upper surface of the horizontal bar 24, which has the upturned ends 25, to which are pivoted the rear arms 26 of the side frames or arm rests, which have the horizontal arm rests 27 pivoted on the upper ends of the bars 26 and in turn pivoted at their front ends to the vertical arms or levers 28 of the erecting ball, which is pivoted to the inner side of the main frame tubes 12 at 29, these arms 28 being preferably shaped, as shown, in substantially an ogee curve to

bring the horizontal connecting bar 30 constituting the horizontal portion of the bail in proper relationship to the wheel frames. The front end of the seat 23 is secured to the bar 31 corresponding to the rear bar 24, which bar has the stop lug 32 depending downwardly from its center for the purpose to be hereinafter described. The bars 24 and 31 are riveted at their ends to the horizontal bars 33, which are located directly beneath the edges of the seat, and riveted upon these bars 33 are the spring bars 34 having the central horizontal portions thereof in contact with the under side of the bars 33, while their rear ends 35 are curved through substantially three-quarters of a circle, and have their ends riveted on the twisted portions 36 of the bar 13. The forward ends of these spring bars have the slightly inclined portions 37, which terminate in the curved ends 38, corresponding to the rear curved ends 35, but somewhat smaller, and these spring ends 38 are riveted, as best seen in Fig. 2, to a bracket 39 secured to the inner end of the rivets 29 upon which the arms 28 of the erecting bail are pivoted, the erecting bail being interposed between the tubular sides 12 of the main frame and the vertical portion 12 of the angular brackets 39. By the construction shown, I have secured a very elastic cushioned seat that is held a few inches above the main frame, so as to furnish room beneath it for the drawer 40, which, as best seen in Figs. 3, 4 and 5, preferably consists of a rectangular frame made up of the rear rod 41 and a bar 42 bent into a U-shape so as to form the front and sides of the top of the drawer. The sides of this bar 42 have their upper edges bent to form the hooked flanges 43 which slide in the reversely hooked flanges of the guideway bars 45 secured to the under side of the bars 33, preferably being riveted between said bars 33 and the horizontal portions 34 of the supporting springs. The front portion of the bar 42 has the stiffening member 46 secured to and depending downward therefrom to form the front of the drawer, and this member 46 has the horizontal portion 47 extending rearwardly therefrom, while the sides and bottom of the drawer are formed by the fabric 48 secured to the top of the rectangular frame and inclosing the stiffening portions 46 and 47. This drawer is held in its closed position by the top of the front contacting with the stop lug 32, while said lug similarly contacts with the bar 41 at the rear of the drawer to prevent its being accidentally drawn out of the supporting ways. A flexible loop 49 is provided to enable the drawer to be readily manipulated.

The back rest 50 is constructed like the body of the seat, and has its sides and top secured in the metal frame 51, which is U-shaped in cross section for most of its length,

and is also U-shaped in its general design, the ends 52 thereof, however, being flattened and pivoted on the same rivets 53 by which the side-frame bars 26 are pivoted on the upturned ends 25 of the bar 24. This back 70 frame is held in a plurality of positions by the bail 54, best seen in Fig. 10, which is preferably made of a heavy wire and is of a general U-shape, it being pivoted at its ends by loops encircling the headed studs 55 projecting inwardly from the upper ends of the side pieces 26 to which they are secured. The back 50 has a flat metal bar 56 secured to and extending horizontally across the back side thereof below the center, and has 80 the forwardly projecting short arms 57 at its ends. The bail 54 has the upwardly extending portions 58 at its ends connected by the curves 59 with the normally vertical portions 60, and, as shown in Fig. 10, when the 85 bail is in the full-line position, the back 50, through the ends of the bar 56, is held in a vertical position, between the arms 26 and the vertical portion 60 of the bail 54, and being thus substantially attached to the arms 90 26, will be collapsed therewith when the sulky is collapsed. The bar 56 in turn reacts on the bail 54 and holds it in the full-line position, but it will be obvious that when the bail is forcibly pulled up to the 95 dotted-line position shown in Fig. 10, it will be sprung sufficiently to relieve it from the holding action of the flat side of the bar 56 co-operating with the vertical portion 60, and it may then be swung up farther so as to release the bail from any confining action of the bar 51, in which position the back can be swung rearwardly either to the extreme 100 limit shown in dotted lines in Fig. 4, where the back rests against the bail, or to an intermediate position, shown in full lines in Fig. 4, where the ends of the bars 56 enter the loops 61 being formed in the vertical portion 60 of the bail. By the simple mechanism here shown, I have formed a very effective and efficient lock for holding the 105 back, when the parts are erected, in a vertical position, so that it will collapse automatically with the side frames when they are collapsed, and also one in which the back 110 can be adjusted in the plurality of reclining positions shown.

Riveted to the inner sides of the side tubes 12 are the rectangular plates 62, having the inturned flanges 63 at their ends, the upper portions of the plates 62 being utilized to secure the mud guards (not shown), while the lower portions serve as a hinge for the side frames 64, which are preferably formed of sheet metal, of a generally triangular shape, said side frames 64 having the wheel axles or studs 65 rigidly secured and projecting outwardly from the lower ends thereof, and upon which the customary wheels 6, 6 are mounted. The sides 115 120 125 130

64 have the flanges 65 projecting from the edges thereof and above the bodies of the wheel frames, extended into the ears 66 coöperating with the flanges 63 of the plates 62. A rod 67 is fastened in the flanges 63 and serves as a pintle for the hinge formed by the flanges 63 and the ears 66, and to collapse the wheels automatically when they are released, I mount on the rod 67 a helically-coiled torsional spring 68, one end of which reacts against the bottom of the plate 62, as seen at 69, Fig. 1, while the other end 70, as seen in the same figure, reacts against the top of the wheel frame 64, so that the spring always tends to throw the wheel frames to the collapsed position shown in Fig. 6. Secured to the bottom of the wheel frame 64 is the sheet-metal bracket 71, preferably formed integral with the wheel frame by properly shaping the parts and riveting them together, as best seen in the perspective view constituting Fig. 12. This bracket 71 has the hook 72 to receive the lower ends of the levers 28 of the erecting bail when the parts are in their erected position, and it also has the cam portion 73, which is a continuation of one of the substantially vertical flanges forming the sides of the wheel frame; and when the sulky is to be erected, the arms 28 engaging these cams 73 force the wheel frames out into their erected position as the erecting bail moves downwardly and forwardly. One of these brackets 71 has its cam surface arranged to act slightly in advance of the other; so that when the wheels are automatically collapsed, one wheel will fold sufficiently in advance of the other to prevent any interference.

40 Pivoted to the inner edges of the forward portion of the bars 12 by the rivets 74 is the front standard 75, which is preferably formed of a metal bar of substantially U-shape in its general outline except that it has inclined portions 76 near its upper end to narrow the frame so that the pair of bars 79 constituting the frame for the foot rest 80 may be pivoted thereto at 81 at the proper distance apart. The rear ends of these bars 79 are bent somewhat to cause them to diverge, and they are pivoted at said rear ends, by the rivets 82, to the lower ends of the levers 28 of the erecting bail. As the parts are collapsed, the standard 78 and the foot rest and its supporting bars will be folded rearwardly and upwardly between the wheel frames and the seat, as seen in Fig. 6. It will be noted from Fig. 2 that the foot rest 80 is made of a piece of sheet-metal stamped into the shape shown, and riveted to the bars 79.

The tongue 83 is preferably formed of sheet metal, with its body portion bent into an inverted U-shape in cross section, and has 65 the forked handle 84 formed at its upper end. At its lower end, it is riveted and bolted to two bars 85, forming extensions thereof, the bars 85 having their forward ends bent to form an angular portion, one arm of which engages the tongue proper, 70 while the other arm is riveted to the reinforcing bar 86 extending at right angles across the rear end of the tongue proper. Beyond this bar 86, the bars 85 are bent inwardly in a curve to accommodate the 75 curved portions 17 of the side bars, and are fulcrumed at 87 to the inner sides of the side bars 12. The tongue proper and the extensions 85 together form an operating lever, of which the tongue proper is the 80 power arm, while the rivets 87 are the fulcrum, and the portions to the rear of the rivets 87 are the load arms, which have the links 88 pivoted to their rear ends. These links 88 are curved outward and upward, 85 and are pivoted at 89 to the levers 28 of the erecting bail, and also to the parallel bars 90, which are pivoted at their rear ends to the arms 26. With the construction shown, it will be obvious that as the tongue is 90 swung upward and rearward from the position shown in Fig. 1, the links 88 will be drawn downward and forward, thereby collapsing the side frames, foot rest and standard by positive connections to the collapsed 95 position shown in Fig. 6.

To lock the tongue in its extended position, and thus lock the parts in their erected position, I provide the locking mechanism best shown in Fig. 1, where it will be seen 100 that the lock 91, preferably formed of sheet metal, has the upwardly extending ears 92 by which it is pivoted to the tongue, and the locking recess 93 formed in the body thereof, which coöperates with the cross piece 19 105 connecting the forward ends of the side tubes 12. Beyond this locking recess 93 is a cam portion 94, which is so shaped and so held as to engage the upper surface of the recess 20 in the locking bar 19 when 110 the tongue is swung down so as to cam the lock back and allow it to pass the bar 19. The rear portion 95 forms a handle for the lock, and to hold the lock in its operative position and at the same time prevent its 115 possibly being thrown far enough out of its normal position to prevent the cam surface 94 from engaging the upper edge of the bar 19, I interpose the helically-coiled expanding spring 96 between the under side of 120 the handle 83 and the upper side lock 91. A bolt 97, headed at both ends, and passing through suitable apertures in the tongue and lock, prevents the lock from moving far enough to get out of its proper engaging 125 position when the tongue is swung down. When the cart is collapsed, the handle 83 engages a spring-locking tongue 98, best seen in Fig. 9, which is rigidly secured to and projects rearwardly from the bar 56 130

secured to the back 50. This tongue 98 has a cam surface 99 thereon to force the tongue to one side sufficiently to cause it to lock when it is swung down into collapsing position.

The operation of my improved sulky will be readily apparent. Assuming that the sulky is in the erected position shown in Fig. 1, and it is desired to collapse the same, 10 the back, if it should be in the inclined position, is first brought into the vertical position shown in Fig. 10, where it is secured by the action of the bail 54 on the bar 56. The lock 91 is now moved to release the 15 locking recess 93 from the connecting bar 19, after which the tongue is swung upwardly and rearwardly, it serving in this action as a lever to automatically collapse all the parts, and as they are collapsed, the 20 wheels still remain erect, as indicated in dotted lines in Fig. 6, where the dotted line 100 indicates the floor line at this time, the forward part of the cart falling down to the floor as the tongue is swung rearwardly 25 and caught under the catch 98. As soon as it is caught, the movement of the handle is reversed, *i. e.*, it is then lifted up, and it turns on the rear end of the tongue, now resting on the floor as a pivot, and as soon as 30 the wheels are lifted clear of the floor, the springs throw them to closed position, thus making an extremely simple and effective collapsing action. When the sulky is to be erected, the handle is unlocked from the 35 catch 98 and swung forward, when the parts will be positively erected by the connections shown and described, the erecting bail also serving to erect the wheel frames against the resistance of the springs 68.

40 While I have shown and described my invention as embodied in the form which I at present consider best adapted to carry out its purposes, it will be understood that it is capable of modifications, and that I do 45 not desire to be limited in the interpretation of the following claims except as may be necessitated by the state of the prior art.

What I claim as new, and desire to secure by Letters Patent of the United States, is:

50 1. In a child's collapsible vehicle, the combination with a main frame, of a pair of collapsible wheel frames pivoted thereto, wheels journaled on said wheel frames, a folding hand lever fulcrumed on the main frame, connections between the wheel frames and hand lever for erecting the former as the latter is swung to its open position, and springs for automatically collapsing the wheel frames when the hand 55 lever has been folded and the wheels are raised from the ground.

2. In a child's collapsible vehicle, the combination with a main frame, of a pair of collapsible wheel frames pivoted thereto,

wheels journaled on said wheel frames, a pair of side frames pivoted above the wheel frames, a folding hand lever fulcrumed on the main frame, connections between the wheel frames, side frames and hand lever for erecting said frames as the lever is 70 swung to its open position, and springs for automatically collapsing the wheel frames when the hand lever has been folded and the wheels are raised from the ground.

3. In a child's collapsible vehicle, the combination with a main frame, of a pair of collapsible wheel frames pivoted thereto, wheels journaled on said wheel frames, a standard fulcrumed beneath the forward end of the main frame, a folding hand lever 80 fulcrumed on the main frame, connections between the wheel frames, the standard and hand lever for erecting the wheel frames and standard as the lever is swung to its open position, and springs for automatically 85 collapsing the wheel frames when the hand lever has been folded and the wheels are raised from the ground.

4. In a child's collapsible vehicle, the combination with a main frame, of a pair of collapsible wheel frames pivoted thereto, wheels journaled on said wheel frames, a foot rest pivotally supported beneath the forward end of the main frame, a folding hand lever fulcrumed on the main frame, connections between the wheel frames, the foot rest and hand lever for erecting the wheel frames and foot rest as the lever is swung to its open position, and springs for automatically 95 collapsing the wheel frames when the hand 100 lever has been folded and the wheels are raised from the ground.

5. In a child's collapsible vehicle, the combination with a main frame, of a pair of collapsible wheel frames pivoted thereto, wheels journaled on said wheel frames, a back rest pivoted above the rear of the wheel frames, a folding hand lever fulcrumed on the main frame, connections between the wheel frames, back rest and hand lever for 110 erecting the wheel frames and back rest as the lever is swung to its open position, and springs for automatically collapsing the wheel frames when the hand lever has been folded and the wheels are raised from the 115 ground.

6. In a child's collapsible vehicle, the combination with a main frame, of a pair of collapsible wheel frames pivoted thereto, wheels journaled on said wheel frames, a pair of side frames pivoted above the wheel frames, a back rest connected to the side frames and moving therewith, a folding hand lever fulcrumed on the frame, connections between the wheel frames, side frames, back rest and hand lever for erecting the side frames and back rest as the hand lever is swung to its open position, and springs 120 125

for automatically collapsing the wheel frames when the hand lever has been folded and the wheels are raised from the ground.

7. In a child's collapsible vehicle, the combination with a main frame, of a pair of collapsible wheel frames pivoted thereto, wheels journaled on said wheel frames, a standard fulcrumed beneath the forward end of the main frame, a foot rest connected to and extending rearward from the standard beneath the main frame, a folding hand lever fulcrumed on the main frame, connections between the wheel frames, standard, foot rest and hand lever for erecting the wheel frames, standard and foot rest as the handle is swung to its open position, and springs for automatically collapsing the wheel frames when the hand lever has been folded and the wheels are raised from the ground.

8. In a child's collapsible vehicle, the combination with a main frame, of a pair of collapsible wheel frames pivoted thereto, wheels journaled on said wheel frames, a pair of side frames pivoted above the wheel frames, a standard fulcrumed beneath the forward end of the main frame, a folding hand lever fulcrumed on the main frame, connections between the wheel frames, side frames and hand lever for erecting the wheel frames, side frames and standard as the hand lever is swung to its open position, and springs for automatically collapsing the wheel frames when the hand lever has been folded and the wheels are raised from the ground.

9. In a child's collapsible vehicle, the combination with a main frame, of a pair of collapsible wheel frames pivoted thereto, wheels journaled on said wheel frames, a pair of side frames pivoted above the wheel frames, a foot rest pivotally supported beneath the forward end of the main frame and movable toward and from said frame, a folding hand lever fulcrumed on the main frame, connections between the wheel frames, side frames, foot rest and hand lever for erecting the wheel frames, side frames and foot rest as the lever is swung to its open position, and springs for automatically collapsing the wheel frames when the hand lever has been folded and the wheels are raised from the ground.

10. In a child's collapsible vehicle, the combination with a main frame, of a pair of collapsible wheel frames pivoted thereto, wheels journaled on said wheel frames, a standard fulcrumed beneath the forward end of the main frame, a back rest pivoted above the rear end of the main frame, a folding hand lever fulcrumed on the main frame, connections between the wheel frames, standard, back rest and hand lever for erecting the wheel frames, standard and back rest as the lever is swung to its open position,

tion, and springs for automatically collapsing the wheel frames when the hand lever has been folded and the wheels are raised from the ground.

11. In a child's collapsible vehicle, the combination with a main frame, of a pair of collapsible wheel frames pivoted thereto, wheels journaled on said wheel frames, a pair of side frames pivoted above the wheel frames, a standard fulcrumed beneath the forward end of the main frame, a foot rest connected to the standard and extending rearwardly therefrom beneath the main frame, a folding hand lever fulcrumed on the main frame, connections between the wheel frames, side frames, standard, foot rest and hand lever for erecting the wheel frames, side frames, standard and foot rest as the lever is swung to its open position, and springs for automatically collapsing the wheel frames when the hand lever has been folded and the wheels are raised from the ground.

12. In a child's collapsible vehicle, the combination with a main frame, of a pair of collapsible wheel frames pivoted thereto, wheels journaled on said wheel frames, a collapsible standard depending from the forward end of the main frame, a foot rest connected to the standard and extending rearwardly therefrom beneath the main frame, a back rest pivoted above the rear end of the main frame, a folding hand lever fulcrumed on the main frame, connections between the wheel frames, standard, foot rest, back rest and hand lever for erecting the wheel frames, standard, foot rest and back rest as the lever is swung to its open position, and springs for automatically collapsing the wheel frames when the hand lever has been folded and the wheels are raised from the ground.

13. In a child's collapsible vehicle, the combination with a main frame, of a pair of collapsible wheel frames pivoted thereto, wheels journaled on said wheel frames, a pair of side frames pivoted above the wheel frames, a standard fulcrumed beneath the forward end of the main frame, a back rest pivoted above the rear end of the main frame, a folding hand lever fulcrumed on the main frame, connections between the wheel frames, side frames, standard, back rest and hand lever for erecting the wheel frames, side frames, standard and back rest as the lever is swung to its open position, and springs for automatically collapsing the wheel frames when the hand lever has been folded and the wheels are raised from the ground.

14. In a child's collapsible vehicle, the combination with a main frame, of a pair of collapsible wheel frames pivoted thereto, wheels journaled on said wheel frames, a pair of side frames pivoted above the wheel frames,

frames, a back rest pivoted above the rear of the main frame and connected to the side frames to collapse therewith, a standard fulcrumed beneath the forward end of the main frame, a foot rest connected to the standard and extending rearward therefrom beneath the main frame, a folding hand lever fulcrumed on the main frame, connections between the wheel frames, side frames, standard, foot rest and hand lever for erecting the wheel frames, side frames, back rest, standard and foot rest as the lever is swung to its open position, and springs for automatically collapsing the wheel frames when the hand lever has been folded and the wheels are raised from the ground.

15. In a child's collapsible vehicle, the combination with a main frame, of a pair of collapsible wheel frames pivoted thereto, wheels journaled on said wheel frames, a draft tongue fulcrumed on the forward end of the main frame, an erecting frame co-operating with the wheel frames fulcrumed on the main frame, a standard pivoted to the front end of the main frame, and links connecting the erecting frame and the draft tongue and erecting frame and standard, whereby the swinging of the draft tongue erects the wheel frames and standard, substantially as shown and described.

16. In a child's collapsible sulky, the combination with a main frame, of a pair of collapsible wheel frames pivoted thereto, wheels journaled on said wheel frames, a draft tongue fulcrumed on the forward end of the main frame, an erecting frame co-operating with the wheel frames fulcrumed on the main frame, a standard pivoted to the front end of the main frame, a foot-rest frame connecting the erecting frame and the standard, and links connecting the erecting frame and the draft tongue, whereby the swinging of the draft tongue serves to erect the wheel frames, standard and foot rest.

45. 17. In a child's collapsible sulky, the combination with a main frame, of a pair of collapsible wheel frames pivoted thereto, wheels journaled on said wheel frames, a draft tongue fulcrumed on the forward end of the main frame, an erecting frame co-operating with the wheel frames fulcrumed on the main frame and forming the forward sides of a side frame, a seat above the main frame, springs interposed between the main frame and seat, side-frame bars pivoted at the lower ends to the rear portion of said seat, a pair of horizontal connecting pieces for the side-frame bars and the sides of the side frame formed by the erecting frame, and connections between said tongue and erecting frame, for the purpose described.

18. In a child's vehicle, the combination with running gears including the main frame, of a seat carried thereby, and springs interposed between the corners of the seat

and the main frame, said springs being formed by a pair of strips of spring metal secured at their middle to the under side of the seat and having their ends curved through three-quarters of a spire and secured to the main frame.

19. In a child's collapsible sulky, the combination with a main frame consisting of two side bars rigidly connected at their forward ends and having the downturned rear ends forming an anti-tipping support and one pair of the four supports to hold the sulky collapsed in a vertical position, of a U-shaped cross-bar having its transverse portion spacing the rear ends of the main frame and its sides secured to said main frame and its ends forming the other pair of said four supports.

20. In a child's collapsible sulky, the combination with a main frame consisting of two side bars rigidly connected at their forward ends and having the downturned rear ends forming an anti-tipping support and one pair of the four supports to hold the sulky collapsed in a vertical position, of a U-shaped cross-bar having its transverse portion spacing the rear ends of the main frame and its sides secured to said main frame and its ends forming the other pair of said four supports, a pair of flat leaf springs having the horizontal centers to which a seat is secured and the three-quarter spiral ends, one pair of said ends being secured to the transverse portion of the U-shaped bar, while the other pair of said ends of said springs are suitably secured to the side bars, and a seat secured to the horizontal portion of said springs.

21. In a child's collapsible vehicle, a wheel frame formed of a sheet of metal having flanges turned over from the body thereof, said flanges forming ears for the hinges, a cam surface, and a hook.

22. In a child's collapsible vehicle, a wheel frame formed of a sheet of metal having flanges turned over from the body thereof, said flanges forming ears for the hinges, a cam surface, a hook, and a brace arm located at right angles to the hook and riveted to the body of the wheel frame.

23. In a device of the class described, a foot-rest frame consisting of a single sheet of metal formed into a grid-shape and having means formed integral therewith for securing it to the foot-rest frame supporting-bars.

24. In a child's vehicle, the combination with a seat, of side-frame bars extending upwardly therefrom, a back rest pivoted to the rear of the bottom of the seat and having a pair of flat extensions extending from its sides, and a bail pivoted to the side-frame bars near the height of the extensions and shaped so that it co-operates with the flat surfaces of the extension to hold the back

rest in its vertical position, said bail being arranged to swing on its pivots to release it from the extensions.

25. In a child's vehicle, the combination with a seat, of side-frame bars extending upwardly therefrom, a back rest pivoted to the rear of the bottom of the seat and having a pair of flat extensions projecting from its sides, and a spring bail pivoted to the side-frame bars near the extensions and shaped so that it coöperates with the flat surfaces of the extensions to hold the back rest in its vertical position, said bail being arranged to yield by spring action sufficiently to swing it on its pivots to release it from the extensions.

26. In a child's vehicle, the combination with a seat, of side-frame bars extending upwardly therefrom, a back rest pivoted to the rear of the bottom of the seat and having a pair of flat extensions extending from its sides, and a bail pivoted to the side-frame bars near the height of the extensions and shaped so that it coöperates with the flat surfaces of the extensions to hold the back rest in its vertical position, said bail being arranged to swing on its pivots to release it from the extensions, and having a pair of recesses in its sides to receive the extensions and hold the back rest in a reclining position.

27. In a child's vehicle, the combination with a seat, of side-frame bars extending upwardly therefrom, a back rest pivoted to the rear of the bottom of the seat and having a pair of flat extensions extending from its sides, and a bail pivoted to the side-frame bars near the height of the extensions and shaped so that it coöperates with the flat surfaces of the extensions to hold the back rest in its vertical position, said bail being arranged to swing on its pivots to release it from the extensions, and having a pair of

recesses in its sides to receive the extensions and hold the back rest in a reclining position, said back rest being adapted to rest against the transverse portion of the bail for its greatest reclining position.

28. In a child's sulky, the combination with running gears having a main frame, of a tongue pivoted in the forward end thereof, a locking projection carried by the main frame, a catch pivoted to the tongue and having a locking recess coöperating with the projection, and a spring to hold the recess in engagement with the projection.

29. In a child's sulky, the combination with running gears having a main frame, of a tongue pivoted in the forward end thereof, a locking projection carried by the main frame, a catch pivoted to the tongue and having a locking recess coöperating with the projection, and a spring to hold the recess in engagement with the projection, said catch having a cam surface struck by the projection to open it against the action of the spring.

30. In a child's sulky, the combination with running gears having a main frame, of a tongue pivoted in the forward end thereof, a locking projection carried by the main frame, a catch pivoted to the tongue and having a locking recess coöperating with the projection, a spring to hold the recess in engagement with the projection, said catch having a cam surface struck by the projection to open it against the action of the spring, and means to prevent the catch from swinging too far under the tension of the spring.

In witness whereof, I have hereunto set my hand and affixed my seal, this 31st day of December A. D. 1915.

REINHARDT H. BROWN. [L. 8.]

Witness:

JOHN HOWARD McELROY.
